DOOR STOP FOR AUTOMOBILE DOORS

Harvey D. Geyer, Dayton, Ohio, assignor to General Motors Corporation, Detroit, Mich., a corporation of Delaware

Application August 3, 1934, Serial No. 738,176

5 Claims. (Cl. 16—86)

This invention relates to door stops, especially for automobile body doors.

An object of this invention is to provide a resilient door stop which is but slightly flexible 5 in a vertical direction so as to permit only a possibly desired slight vertical movement of the closed door, but which has a substantial flexibility in a horizontal direction so as to yield materially when the door is pressed thereagainst 10 in closing.

Another object is to provide such a resilient door stop which yields in a fore and aft direction without sliding of surfaces upon each other and hence without squeaking or wear.

15 Another object is to provide such a door stop having an insulating resilient non-metallic cushion between the metallic keeper recess and the door jamb, which properly sustains the closed door against excessive vertical movement but nevertheless yields in other directions by a distortion of the resilient cushion without sliding 20 of adjacent surfaces upon each other, whereby to eliminate squeaking noises at the junction of the closed door and door jamb fixed to the body.

25 An important feature of the invention is the simplicity and economy of manufacture of the assembly of parts which provides the above objects.

30 Further objects and advantages of the present invention will be apparent from the following description, reference being had to the accompanying drawing, wherein a preferred embodiment of the present invention is clearly shown.

In the drawing:

35 Fig. 1 is a face view of the dovetail keeper which is fixed to the vertical door jamb. The metal cover plate is shown broken away on the left side of the figure to better show the interior structure.

40 Fig. 2 is a section on line 2—2 of Fig. 1.

Fig. 3 is a horizontal section showing the tapered male wedge plate on the door about to enter the tapered female keeper on the door jamb. The section through the keeper is taken 45 on line 3—3 of Fig. 2.

Fig. 4 is a section on line 4—4 of Fig. 2.

Fig. 5 is a face view of the tapered male wedge plate.

50 Figs. 6, 7 and 8 are views of the metal keeper recess member, Fig. 6 being a face view, Fig. 7 a side elevation, and Fig. 8 an end view from the direction of arrow 8 of Fig. 6.

Similar reference characters refer to similar parts throughout the several views.

55 The keeper assembly as shown comprises an

open top and open front pressed metal housing 10 having two apertured attachment ears 11 thereon, a pressed metal keeper recess member 12 resiliently retained within housing 10 by two portions 13 of soft rubber, and two pairs of hollow metal rollers 14 individually embedded in the rubber 13 and located between member 12 and the ends of housing 10 as best shown in Fig. 1. The metal parts 10, 12 and 14 are bonded by vulcanization in situ to the rubber portions 13 10 by properly locating these metal parts in the vulcanizing mold as inserts. Thus keeper member 12 and metal rollers 14 are very securely but resiliently retained in place within housing 10 in a highly simple and efficient manner. 15

Preferably rollers 14 are spaced slightly from both the end wall 16 of housing 10 and the metal flange 15 of keeper 12, so that there will be small intervening layers 17 of rubber 13, as best shown in Fig. 2. Metal rollers 14 are thus completely 20 isolated by soft rubber from other metal parts and are thus permitted to roll or turn upon their axes by internal distortion of rubber 13. Their function is to substantially limit the endwise resilient movement of keeper member 12 within 25 housing 10 and yet at the same time to permit relatively free in and out resilient movement of keeper 12 relative to housing 10. For instance in Fig. 1, the keeper 12 is permitted to quite freely 30 move up toward the back 9 of housing 10 by the resilient distortion of the two end blocks 13 of rubber while the four metal rollers 14 have a sort 35 of rolling motion within the rubber even though they are entirely surrounded by the soft rubber. However rollers 14 materially limit the relative movement of keeper 12 to the right or left in Fig. 1 since these rollers then function as non-compressible reinforcements in the otherwise resilient 40 end cushions 13. This latter restricted movement is the vertical resilient movement of keeper 12 when assembled upon the door jamb 20, as shown in Fig. 3, and obviously may be made as small as desired by reducing the thickness of the rubber layers 17. The above described relatively free in and out movement of keeper 12 45 is caused by the wedge plate 21 fixed to the door 22 entering the tapered recess 12' in keeper 12 when the door is forced to closed position, and will be hereinafter termed the "closing movement" of keeper 12. 50

In order to render this closing movement of keeper 12 more free and easy, a clearance space 25 is provided between housing 10 and the parts 12, 13 and 14 which move relatively thereto (see Fig. 2). Obviously this clearance space 25 also 55

prevents noise or rattling by preventing contact between housing 10 and keeper 12 and rollers 14 at all times. A clearance space 26 between the rear wall 9 of housing 10 and the movable parts 12, 13 and 14 is made sufficiently large that these movable parts will not contact this rear wall 9 during any closing movement of keeper 12. These clearance spaces 25 and 26 are provided by suitable cores when the parts 10, 12, 13 and 14 are assembled by being vulcanized in situ in a mold as described above. This keeper assembly is fixed to the door jamb 20 by two large end screws 27 extending through the ears 11. A metal cover plate 30 encloses housing 10 and is fixed thereabove by screws 27 and may have a small front flange 28 fixed to the door jamb by two small screws 28. This cover plate 30 is cut away, as at 31, to permit the door wedge plate 21 to enter the tapered recess 12' of keeper 12 and to clear same at all times. In operation, when door 22 is forced or banged closed the wedge plate 21 first enters and abuts the tapered recess 12' in keeper 12, and thereafter the shock of closing the door is absorbed by the resilient closing movement of keeper 12 as described in detail above. The door is held closed by the usual latch or lock against the tendency of keeper 12 to spring outwardly again. When in closed position the swinging edge of the door is resiliently sustained against up or down movement by the restricted vertical movement of keeper 12 as described above. All rattling or squeaking door noises ordinarily occurring in automobile doors are prevented by the elimination of all sliding or other contact between relatively moving parts in the keeper assembly.

While the embodiment of the present invention as herein disclosed, constitutes a preferred form, it is to be understood that other forms might be adopted, all coming within the scope of the claims which follow.

What is claimed is as follows:

1. A door stop for automobile doors comprising a keeper assembly fixed to the door jamb for receiving a projection fixed to the door, said keeper assembly comprising: a fixed base, and a metal keeper resiliently supported upon said base by resilient rubber and having a relatively restricted vertical movement which is opposed by a direct

compression on the supporting rubber and a relatively free door-closing movement relative to said base which is opposed by shear in said supporting rubber.

2. A door stop for automobile doors comprising a keeper assembly fixed to the door jamb for receiving a lateral projection fixed to the door, said keeper assembly comprising: a fixed housing, and a rigid keeper resiliently supported within said housing by soft rubber vulcanized in situ to both said keeper and housing in such manner that the door-closing movement of said keeper is resisted by shear in said supporting soft rubber, said rubber having clearance at the back thereof to prevent direct compression of said rubber by the door-closing movement.

3. A door stop for automobile doors comprising a keeper assembly fixed to the door jamb for receiving a projection fixed to the door, said keeper assembly comprising: a fixed housing, and a rigid keeper resiliently supported within said housing by soft rubber vulcanized in situ to both said keeper and housing, and an insert in said soft rubber which restricts vertical movement but permits relatively free door-closing movement of said keeper.

4. A door stop for automobile doors comprising a keeper assembly fixed to the door jamb for receiving a projection fixed to the door, said keeper assembly comprising: a fixed housing, and a rigid keeper located within but isolated from said housing by resilient rubber, and an insert in said rubber which restricts vertical movement but permits relatively free door-closing movement of said keeper.

5. A door stop bumper assembly for automobile doors, comprising: a housing adapted to be fixed to the door jamb, and a keeper member resiliently supported by said housing by a connection of soft rubber, said keeper member having a relatively restricted vertical movement and a relatively free door-closing movement relative to said housing, said soft rubber being so arranged that it resists door-closing movement only by shear in the rubber but resists vertical movement of said keeper by a direct compression on the rubber.
